HAND BRAKE

Roland J. Olander, Chicago, Ill., assignor to W. H. Miner, Inc., Chicago, Ill., a corporation of Delaware

Application October 29, 1945, Serial No. 625,353

4 Claims. (Cl. 74—491)

1

This invention relates to improvements in hand brakes for railway cars.

One object of the invention is to provide in connection with a ratchet hand brake mechanism for railway cars which is inaccessible from the exterior of the car, simple and efficient means for actuating the holding dog from the exterior of the car.

Other objects of the invention will more clearly appear from the description and claims herein-after following.

In the drawing forming a part of this specification, Figure 1 is a transverse, vertical sectional view through the wall structure of the vestibule section at the platform end of a railway passenger car, illustrating my improvements in connection therewith. Figure 2 is a horizontal sectional view, corresponding substantially to the line 2—2 of Figure 1. Figure 3 is a view, similar to Figure 1, on an enlarged scale and partly broken away, showing the brake housing partly broken away and certain parts therein in vertical section. Figure 4 is a vertical sectional view, corresponding substantially to the offset line 4—4 of Figure 2, said view being on an enlarged scale and partly broken away and illustrating the locking dog in disengaged position.

In said drawing, 10 indicates the transverse end wall of a railway car provided with the usual end platform and vestibule construction, the vestibule diaphragm member at one side of the end of the car only being shown, the same being indicated by 11 in Figure 2. The vestibule post or side wall at the corresponding side of the car, to which the diaphragm is connected, is indicated by 12. The post is of the usual form, being a vertically disposed I beam member. A portion of the end platform of the car is shown in Figure 2, the same being indicated by 13.

The hand brake mechanism proper, which is of a well-known design is mounted on the inner side of the wall 12, being contained within the housing 14 secured to said side wall. The hand brake mechanism shown is of the lever operated ratchet type, including the usual chain winding drum, shown in dotted lines in Figure 2 and indicated by 15. The drum 15 is driven by the usual power multiplying gear and pinion arrangement, not shown, the pinion being carried by a transverse, rotary shaft 16 mounted within the housing, parallel to the wall 12 and meshing with the gear which is located above the same, as shown in dotted lines and indicated by 17 in Figure 2. The gear 17 and the drum 15 are carried on a shaft 18 located above the shaft 16. The shaft

2

16 is rotated by a swinging operating lever 19, journaled on said shaft and carrying a spring actuated pawl 20, which engages a ratchet wheel 21 fixed to the shaft 16. In Figures 1 and 3, the operating lever is shown in its pendant position with the pawl 20 disengaged from the ratchet wheel, the pawl being so held by a fixed stop member 22 on the housing. The shaft 16 also has a second ratchet wheel 23 fixed thereto with which a pivoted locking dog 24 engages. The locking dog 24 is mounted on a pivot 25, parallel to the wall 12 of the vestibule of the car and also parallel to the shaft 16. The dog 24 is yieldingly forced against the ratchet wheel by the usual spring 25. This locking dog is lever actuated, being provided with a radially projecting lug or tail piece 26 with which the actuating lever engages.

In carrying out my invention, I provide a lever 20 A on the exterior of the car; a connecting link B or push rod actuated by the lever A; and a lever C actuated by the link B and cooperating with the locking dog to actuate the same.

The lever A is vertically disposed and pivotally supported between its ends on a bracket 26 fixed to the outer side of the wall 12 of the vestibule portion of the car. The bracket 26 has a pair of outstanding, spaced ears 27—27 between which the lever A extends, and a pivot pin 28, extending through said ears and the lever, supports the lever between its ends for swinging movement in a vertical plane. The lower arm of the lever A, which arm is indicated by 29, is provided with a hand grip portion 30 at its bottom end. The upper arm of the lever, which is indicated by 31, extends at an angle to the lower arm, being inclined outwardly away from the wall 12 in upward direction, as clearly shown in Figure 1.

40 The connecting link or push rod B is in the form of an elongated bar extending loosely through the opening 33 in the wall 12. The rod B is horizontally disposed and is forked at its outer end, as indicated at 32, said forked portion being engaged over the upper end portion of the arm 31 of the lever A and pivotally connected to said arm 31 by a pin 34 extending through said arm and elongated slots 134 provided in the arms of the forked portion of said rod. The slots 134 provide a lost motion connection between said rod and the lever A.

45 The lever C is similar to the usual lever member for actuating the locking dog employed in a brake of this type with the exception that it is provided with connecting means at its lower end

for the rod B. This lever C is pivotally supported at its upper end in the usual manner by a pivot element 35 and has a pair of radially projecting, circumferentially spaced lugs 36—36 which engage with the tail piece 126 of the dog to either throw the same into or out of engagement with the ratchet wheel 23. As is well understood by those skilled in this art, the lever C is manually actuated and serves to control the operation of the locking dog from the interior of the vestibule of the car. The means at the lower end of the lever C for connecting the same to the rod B comprises a socket portion 37, receiving the inner end of the rod, and a pivot pin 38 extending through the lever and said end of the rod.

In Figures 1 and 3, the locking dog 24 is shown in position operatively engaging the ratchet wheel 23. To release the dog from the exterior of the car, the attendant pulls the handle lever arm portion 29 of the lever A outwardly away from the wall 12 of the car, thereby swinging the upper arm 31 of the lever inwardly toward said wall, taking up the lost motion, pushing the rod B inwardly, or to the right, as seen in Figure 1, by engagement of the arm 31 of the lever with the wall at the inner end of the forked portion, thereby swinging the lever C in clockwise direction, as viewed in Figure 3, pressing the upper lug 36 of said lever against the tail 126 of the dog and rotating the dog to disengaged position, as shown in Figure 4. In this connection it is pointed out that the lost motion connection between the lever A and the rod B permits swinging movement of the lever C in contra-clockwise direction, as viewed in Figure 1, in effecting forcible engagement of the dog 24 with the ratchet wheel 23, without disturbing the pendant position of the lever A, that is, the lever C may be actuated to engage the dog with the ratchet wheel without effecting movement of the lever A.

I claim:

1. In a mechanism for controlling the operation of the pivoted locking dog of a ratchet brake mounted entirely on the inner side of the wall of a car, the combination with a pivoted lever for actuating said dog mounted at said inner side of said wall, said lever having a hand grip portion; of a rod connected to the hand grip portion of said lever and extending through said wall; and an actuating lever swingingly supported on the outer side of said wall and pivotally connected to the rod for reciprocating the same.

2. In a mechanism for controlling the operation of the pivoted locking dog of a ratchet brake mounted on the inner side of the wall of a car, the combination with a depending lever at said inner side of said wall pivotally supported at its upper end and cooperating with said dog to actu-

ate the same, said lever having a hand grip portion at its lower end; of a horizontally disposed rod engaged at one end with the hand grip portion of said lever to swing the same in a direction to disengage said dog, said rod extending through said wall; and an actuating lever swingingly supported on the outer side of said wall and engaged with the outer end of said rod to actuate the same.

- 10 3. In a mechanism for controlling the operation of the pivoted locking dog of a ratchet brake mounted on the inner side of the wall of a car, the combination with a lever at said inner side of said wall pivotally supported at its upper end and cooperating with the dog to actuate the same, said lever having a hand grip portion at its lower end; of a horizontally disposed rod engaged with the hand grip portion of said lever to swing the same, said rod extending through said wall; and a vertically disposed operating lever swingingly supported between its ends on the outer side of said wall, said last named lever having upper and lower arms, said lower arm terminating in a hand grip portion, the upper end of said upper arm being engaged with the rod to actuate the same.
- 15 4. In a mechanism for controlling the operation of the pivoted locking dog of a ratchet brake mounted on the inner side of the wall of a car, the combination with a depending lever at said inner side of the wall pivotally supported at its upper end and cooperating with said dog to actuate the same, said lever having a hand grip portion at its lower end; of a horizontally disposed rod extending through said wall, said rod being pivotally connected at its inner end to the hand grip portion of said lever; and a vertically disposed operating lever swingingly supported between its ends on the outer side of said wall, said last named lever having a lost motion pivotal connection at its upper end with the outer end of said rod and being provided with a hand grip portion at its lower end.
